US0D1008741S

(12) **United States Design Patent** (10) **Patent No.:** **US D1,008,741 S**
(45) **Date of Patent:** **** Dec. 26, 2023**

(54) **STRAW CUP**

(71) Applicant: **Hongdan Chen**, Guangdong (CN)

(72) Inventor: **Hongdan Chen**, Guangdong (CN)

(**) Term: **15 Years**

(21) Appl. No.: **29/820,656**

(22) Filed: **Dec. 23, 2021**

(30) **Foreign Application Priority Data**

Oct. 9, 2021 (CN) 202130662291.1

(51) **LOC (14) Cl.** **07-01**

(52) **U.S. Cl.**

USPC **D7/534; D7/510**

(58) **Field of Classification Search**

(57) **CLAIM**

The ornamental design for a straw cup, as shown and described.

DESCRIPTION

FIG. 1 is a perspective view of a straw cup showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.

1 Claim, 7 Drawing Sheets
